COMBINED PACKAGING CARD AND HANGER FOR AN ARTICLE OF MERCHANDISE

Charles A. Wells, Coshocton, Ohio, and Robert A. O'Neil and Michael C. Wilson, Wheaton, Ill., assignors to Pretty Products, Inc.

Filed Nov. 15, 1972, Ser. No. 306,848

Term of patent 14 years

Int. Cl. D9—99

U.S. Cl. D9—191

FIG. 1 is a perspective view of a combined packaging card and hanger for an article of merchandise showing our new design with a portion of an article of merchandise being shown in broken lines for illustrative purposes only;

FIG. 2 is a side elevational view on an enlarged scale; and

FIG. 3 is a top plan view thereof.

We claim:

The ornamental design for a combined packaging card and hanger for an article of merchandise, substantially as shown and described.
